E. A. Russell,

By A. Miller Beauford Atty.

UNITED STATES PATENT OFFICE.

ELI A. RUSSELL, OF CHICAGO, ILLINOIS, ASSIGNOR TO STRONGHART COMPANY, OF CHICAGO, ILLINOIS, A CORPORATION OF ILLINOIS.

SMALL SAVINGS BANK.

Application filed July 9, 1921. Serial No. 483,444.

To all whom it may concern:

Be it known that I, ELI A. RUSSELL, a citizen of the United States, residing at Chicago, in the county of Cook and State of Illinois, 5 have invented a certain new and useful Improvement in Small Savings Banks, of which the following is a full, clear, concise, and exact description, reference being had to the accompanying drawings, forming a part of 10 this specification.

My invention relates to small savings banks.

One of the objects of the invention is to provide a practical and durable construction 15 of bank of the class specified.

Another object of the invention is to provide effective means for preventing the escape of coins by falling out of the bank, and and also to prevent their being extracted 20 from the same through the coin slot.

Another object of the invention is to provide an advantageous construction for opening and closing the bank to permit the removal of coins.

25 Another object of the invention is to provide a simple and practical form of locking device for locking the closure in closed position.

In the accompanying drawings Fig. 1 is 30 a side elevation of a bank embodying my present invention;

Fig. 2 is a cross section taken on line 2—2 in Fig. 3;

Fig. 3 is a cross section taken on line 3—3 35 in Fig. 2;

Fig. 4 is a view of a detail of construction with the bank in an upside down position.

Referring to the drawings I show a bank 40 having an outer shell or casing 1 preferably made substantially oblong and rectangular in form, as shown in Figs. 1 and 2, and having a closed top 2, and sides 3—3. A bottom or closure 4 closes the lower open end of the shell or casing 1. A handle 5 is shown secured to the top 2 by means of lugs 6.

A coin slot 7 is shown in one of the sides 3, being of such size as to admit large coins as well as small ones. To prevent the escape 50 or extraction of coins through the slot 7 I show tooth-like members 8—8 mounted side by side on a rod or bar 9 (Fig. 2). The lower ends of these members 8 are prefer-

ably pointed as shown in Fig. 3, and there are preferably washers 10—10 between the successive members, which washers insure independent movement of the several members 8—8. The members 8—8 control a supplemental slot 7^a so that when in a downward position, as shown in Fig. 2, they will effectively close the supplemental slot 7^a, preventing coins from entering slot 7, and thereby preventing escape or extraction through the same. To hold members 8 in such downward position a weight 11 preferably in the form of a roller is arranged above the members 8—8 so that by gravity said roller 11 tends to hold said members 8 always in a downward position.

Furthermore, supplemental slot closing 70 devices are provided, as for example the sliding members 12—12. These members are arranged below the slot 7^a and have their upper ends tooth shaped, and are arranged to slide up and down so that their upper ends 75 will more or less open and close the slot 7^a. The members 12—12 are conveniently arranged to slide in the rear of one wall 13 of a small box or casing 14 secured in position 80 in one corner of the bank as shown in Fig. 2. A strip 15 forms a back for the members 12 so that they slide between said strip 15 and the wall 13. The members 8—8 are also preferably enclosed within the box 14 as are also the bar 9 and roller 11, and the slot 7^a is 85 formed in the wall 13 so that the supplemental slot and the entire slot protecting or coin holding mechanism may be arranged as a single unitary structure to be bodily attached or detached from the interior of the 90 shell or casing 2.

When the bank is in an upright condition as shown in Fig. 2, the members 8—8 will be inclined downwardly with the roller 11 holding them down so that the internal or supplemental slot 7^a will be closed by said members 8. In this position a coin may be inserted by passing it first through the casing slot 7 and then through the supplemental slot 7^a, being allowed to pass through the latter by a slight elevation of the members 8. Passing through these slots the coin drops into the interior of the bank. When in this upright position the coin cannot reenter the slot 7^a, because of the members 8 held down 95 by their own weight and the weight of the 100 105

roller 11. Nor can the coins be extracted through the slot 7^a by tools from the outside, because said slot 7^a is remote from the outer or casing slot 7, making it impossible to gain 5 sufficient access to the members 8 to manipulate them.

When the bank is turned upside down the members 8 will fall downwardly, that is toward the top 1 which is in a downward 10 position as shown in Fig. 4, and the slot 7^a will be opened in so far as the members 8 are concerned, but at this time the other slot closing devices 12 slide downwardly, as shown in Fig. 4, so that they instead of the 15 members 8—8 close the slot 7^a. In fact the lower ends of the members 12 rest upon the members 8. Thus means are provided for constantly closing the slot 7^a, whether the bank is in its usual upright position or in an 20 upside down position, and this together with the fact that a remote or inner slot is controlled rather than the outer shell or casing slot, makes the bank practically proof against any escape or extraction of coins.

25 The bottom 4 is fitted closely within the lower open end of the shell or casing 1 but is capable of removal from said opening, so as to open the bank for the discharge of its contents. Preferably the bottom 4 is made 30 to swing about one end, so that it may move down to position shown in dotted lines in Fig. 3. To such end the right hand end of the bottom 4 is provided with a hinged or swinging connection formed by a pair of 35 grooved members or legs 17 connected by a cross bar 18 and a bracket 19 secured to the casing 1 by rivets 20 and having its sides 21 provided with annular slots 22 in which the bar 18 can work. Thus a hinge connection 40 is provided and it is of such character that a certain amount of play is permitted to insure the proper fitting of the bottom into its opening.

The bottom 4 is provided with a lock 23 45 having a tongue or catch 24 adapted to engage a clip 25 on the shell or casing 1 and thereby lock the bottom 4 in position. The lock 23 is preferably controlled by a key shown in dotted lines at 26 in Fig. 3, whereby the bottom may be locked and unlocked 50 to permit the coins to be discharged from the bank by means of said key 26.

It will be understood that changes and modifications may be made without departing 55 from the spirit of the invention.

What I claim is:

1. A small bank having inner and outer coin slots and means for protecting the inner slot.
- 60 2. A coin bank having inner and outer slots and means for protecting the inner slot comprising means for closing the inner slot when the bank is in an upright position, and also when it is turned upside down.
- 65 3. A coin bank having inner and outer

coin slots and means for protecting the inner slot comprising slot closing devices arranged between the two slots and adapted to admit coins through the inner one from outside, but prevent escape of coins through 70 same from inside.

4. A coin bank having inner and outer coin slots and means for protecting the inner slot comprising swinging members pivotally mounted above said slot and between it and the outer one and arranged to swing into and out of position to close said slot.

5. A coin bank having a coin slot and means for protecting the same comprising 80 swinging members pivotally mounted above the slot and arranged to swing into and out of position to close the slot, in combination with a weight tending to swing said members downwardly.

85 6. A coin bank having a coin slot, a bar extending longitudinally of the slot above the same, swinging members pivotally mounted on the bar and extending to the coin slot and adapted to open and close the 90 same by their swinging movement and a bar or rod arranged above the swinging members and adapted to serve as a weight to normally lower the same.

95 7. A coin bank having a coin slot, a bar extending longitudinally of the slot above the same, swinging members pivotally mounted on the bar and extending to the coin slot and adapted to open and close the 100 same by their swinging movement and a bar or rod arranged above the swinging members and adapted to serve as a weight to normally lower the same, and washers 105 also on said pivotal rod between said members.

10. A coin bank having a coin slot and two separate devices for protecting the same when the bank is in different positions.

9. A coin bank having a coin slot and two separate devices for protecting the same one 110 when the bank is in an upright position and the other one when it is in an upside down position.

10. A coin bank having a coin slot provided with protecting means adapted normally to descend by gravity to protect the slot when the bank is in its normal position, and also having separate means adapted to move by gravity to protect the slot when the bank is in an upside down position.

11. A small bank having a coin slot and sliding members for protecting the same mounted below the slot but arranged to slide by gravity to protect the slot when the bank is upside down.

12. A coin bank having a coin slot in combination with means for protecting said slot with the bank in normal and upside down positions, said means comprising movable members arranged to move into position to 130

- protect the slot when the bank is in normal position, and other movable members arranged to move into position to protect the slot when the bank is in upside down position. 5
13. A coin bank provided with an interiorly arranged box or casing secured to the inner side of the bank adjacent the coin slot of the bank, said box or casing having an inner wall provided with a coin slot opposite the coin slot of the bank and slot protecting means located between the coin slot of the bank and the supplemental coin slot of said wall. 10
14. A coin bank provided with an interiorly arranged box or casing secured to the inner side of the bank adjacent the coin slot of the bank, said box or casing having an inner wall provided with a coin slot opposite the coin slot of the bank and slot protecting means located between the coin slot of the bank and the supplemental coin slot of said wall, said protecting means comprising a bar or rod arranged within and supported by said inner box or casing and swinging members pivotally mounted on said bar or rod and arranged by their swinging movement to more or less open and close said inner slot. 15
15. A small bank having a coin slot and also having an interiorly arranged box or casing secured inside the bank near said slot or casing and having an inner wall provided with a coin slot located opposite said outer slot or casing, and slot protecting devices comprising slidables members mounted within said inner box or casing located below said coin slot thereof, whereby when the bank is turned upside down said members will slide downwardly to more or less close said inner slot. 20
16. A small bank having a coin slot and also having an interiorly arranged box or casing secured within the bank near the wall containing said slot, said box or casing being provided with a supplemental slot located substantially opposite the slot of the bank and spaced inwardly from the same, said box or casing being provided with means for protecting said inner slot. 25
17. A small bank having a coin slot and also having an interiorly arranged box or casing secured within the bank near the wall containing said slot, said box or casing being provided with a supplemental slot located substantially opposite the slot of the bank and spaced inwardly from the same, said box or casing being provided with means for protecting said inner slot, said box or casing with the slot and protecting means thereof being bodily separable from the bank itself. 30
18. A small bank having a closure and means for making a hinge connection between the same and the bank comprising brackets on the closure and bank respectively, one of said brackets being provided with a pin and the other with slots in which said pin may travel to permit opening swinging movement of the closure, each of said brackets having two walls, the pin on one being extended between its walls and the slots of the other being formed in both walls thereof. 35
- In witness whereof, I hereunto subscribe my name this 3rd day of June, A. D., 1921. 40
